UNITED STATES PATENT OFFICE

167,070

PLATE

Stella Davis and Jack Davis, London, England

Application April 16, 1951, Serial No. 14,864
In Great Britain February 16, 1951

Term of patent 3½ years

(Cl. D44—15)

To all whom it may concern:

Be it known that we, Stella Davis and Jack Davis, British subjects, residing at London, England, have invented a new, original, and ornamental Design for a Plate, of which the following is a specification, reference being made to the accompanying drawing, forming part thereof, in which:

Fig. 1 is a top plan view of a plate showing our new design; and

Fig. 2 is a vertical cross-sectional view thereof taken on line II—II of Fig. 1.

We claim:

The ornamental design for a plate, as shown.

STELLA DAVIS.
JACK DAVIS.
